UNITED STATES PATENT OFFICE

171,898

COMBINATION ASH TRAY AND BOOK END

Joseph A. Lagaipa and Lenore Cohen,
Bridgeport, Conn.

Application February 27, 1953, Serial No. 23,821

Term of patent 3½ years

(Cl. D33—1)

To all whom it may concern:

Be it known that we, Joseph A. Lagaipa and Lenore Cohen, citizens of the United States, residing at Bridgeport, county of Fairfield, State of Connecticut, have invented a new, original, and ornamental Design for Combination Ash Tray and Book End, of which the following is a specification, reference being had to the accompanying drawing, forming a part hereof.

The figure is a perspective view of a combination ash tray and book end, showing our new design. The surface appearance of the back and unshown side is like the side shown.

We claim:

The ornamental design for a combination ash tray and book end, substantially as shown and described.
